UNITED STATES PATENT OFFICE.

KONSTANTINE THULANDER, OF ROCKFORD, ILLINOIS, ASSIGNOR TO NATIONAL LOCK CO., OF ROCKFORD, ILLINOIS, A CORPORATION OF ILLINOIS.

DETACHABLE-CYLINDER LOCK.

1,194,682.

Specification of Letters Patent. Patented Aug. 15, 1916.

Application filed April 23, 1915. Serial No. 23,477.

To all whom it may concern:

Be it known that I, KONSTANTINE THULANDER, a subject of the King of Sweden, residing at Rockford, in the county of Winnebago and State of Illinois, have invented 5 certain new and useful Improvements in Detachable-Cylinder Locks, of which the following is a specification.

This invention relates to locks of the detachable cylinder type such as are commonly 10 used on the drawers and covers of desks and like articles of furniture.

The object of the invention is to simplify and cheapen the cost of production of such 15 locks, which object is attained mainly by a reduction of the number of parts heretofore required and an improved construction of the parts employed whereby the manipulation of the lock, especially as regards the insertion and withdrawal of the key cylinder 20 into and from the lock casing is facilitated.

The invention, its manner of use, and its 25 advantages will be readily understood when considered in connection with the following detailed description and the accompanying drawings wherein I have illustrated a practical and approved embodiment of the invention, and in which—

Figure 1 is a front elevation of the lock 30 casing and key cylinder assembled; Fig. 2 is a side elevation of the same, shown as mounted in a mortise in the front wall of a desk drawer or other lock-carrying member; Fig. 3 is a vertical section on the line 3—3 of Fig. 5; Fig. 4 is an elevation showing the body of the lock casing, the bolt, key tumbler, and actuating spring of the cylinder retainer, with the casing cover, key cylinder, and cylinder retainer removed; Fig. 5 is a view similar to Fig. 4, but showing the cylinder retainer in place and in locking engagement with the key cylinder; this figure being taken on the line 5—5 of Fig. 3, in section through the key cylinder; Fig. 6 is a view similar to Fig. 5, but showing the cylinder retainer actuated by inward movement 45 of the bolt to released position relatively to the key cylinder; Fig. 7 is a vertical section on the line 7—7 of Fig. 5, showing the bolt and the cylinder retainer and their co-operating lugs in edge elevation.

Referring to the drawings, 10 designates the body and 11 the cover of an ordinary lock casing employed in locks of this character, these parts being united by rivets 12.

Within the casing are the bolt 13 and tumbler 14 mounted for co-operation with the key in the usual manner, these parts being of the usual construction except that the bolt is formed on one edge with a laterally projecting lug or shoulder 13'; the purpose of which will hereinafter appear.

15 designates the key cylinder that is entered into the lock casing through a hole 16 in the cover 11 and extends through a hole 17 in the rear wall of the body 10. The key cylinder 15 is formed with an annular cam shoulder 18 thereon and an annular locking groove 19 directly in rear of said cam shoulder, as best shown in Fig. 3.

20 designates a cylinder retaining plate that is slidably mounted within the casing above the bolt 13 and tumbler 14, being guided by slots 21 engaging the rivets 12. This retaining plate is formed with a substantially central opening 22 of a size sufficient to admit the passage of the annular cam 18 of the key cylinder therethrough; and said retaining plate is further provided with a laterally projecting lug 20' (Fig. 7) 30 on one edge thereof that extends beneath and across the path of movement of the lug or shoulder 13' of the bolt.

A spring 23 mounted on one of the rivets 12 engages at one end a lug 14' on the tumbler 14 to actuate the latter and at its other end engages an inturned lug 24 on the lower edge of the retaining plate 20, thereby normally forcing the latter outwardly to a position wherein the lower edge of the opening 22 engages the locking groove 19 of the key cylinder 15, thereby locking the key cylinder to the lock casing. In this position of the parts, when the bolt 13 is in its retracted or unlocking position as shown in the several views of the drawings, the shoulder 13' of the bolt lies in engagement with the lug or shoulder 20' of the retaining plate, as clearly shown in Fig. 7.

When it is desired to withdraw the key cylinder in order to remove the lock, or for any other purpose, all that is necessary is to force the bolt 13 inwardly of the casing by means of a suitable tool applied to the outer end of the bolt, and this inward movement of the bolt, through the lugs 13' and 20', transmits an inward or downward movement to the retaining plate 20 that suffices to carry the latter out of engagement with the locking groove 19 of the key cylinder,

thus permitting the latter to be readily withdrawn. When the key cylinder is replaced, all that is necessary is to enter the forward end of the same through the openings 16 and 22 and press thereon, the engagement of the cam 18 with the lower edge of the opening 22 operating to depress the retaining plate until the cam has passed beyond the opening, whereupon the retaining plate instantly snaps into locking position in the groove 19 under the influence of spring 23.

It is obvious to those skilled in the art that the details of structure and relative arrangement as herein shown might be variously modified without involving any substantial change in the structure of its principle of operation. It should therefore be understood that I do not limit myself to the exact construction herein shown and described, but reserve the right to make such variations therein as fairly fall within the spirit and scope of the invention.

I claim:

25 1. In a detachable cylinder-lock, the combination with a lock-casing and bolt, of a detachable key-cylinder, a cylinder-retainer located within said casing; and means whereby said retainer is actuated to cylinder-release position upon movement of said bolt inwardly of said casing.

30 2. In a detachable-cylinder lock, the combination with the lock casing and bolt, of a detachable key cylinder, a cylinder-retainer located within said casing, a spring normally maintaining said retainer in locking relation to said cylinder, and engaging members on said bolt and retainer whereby the latter is moved to cylinder-release position by a movement of said bolt inwardly of said casing.

35 3. In a detachable-cylinder lock, the combination with the lock casing and bolt, of a detachable key cylinder formed with an annular locking groove, a slideable cylinder-retaining plate having a portion thereof adapted to enter said groove, a spring normally maintaining said retaining plate engaged with said groove, and engaging members on said bolt and retaining plate whereby the latter is moved to unlocking position relatively to said cylinder upon a movement of said bolt inwardly of said casing.

4. In a detachable-cylinder lock, the combination with the lock casing, of a bolt having a laterally projecting lug, a detachable key cylinder formed with an annular locking groove, a slideable cylinder-retaining member having a portion thereof adapted to enter said groove and a laterally projecting lug extending across the path of movement of said bolt lug, and a spring normally maintaining said retaining member engaged with said groove.

5. In a detachable-cylinder lock, the combination with the lock casing and bolt, of a slideable cylinder-retaining plate having an opening therethrough for the key cylinder, a key cylinder formed with a cam and a locking groove in rear of said cam adapted to coöperate with an edge portion of said retaining plate around said opening for entering said cylinder through and locking the same to said retaining plate, a spring normally maintaining said retaining plate engaged with said groove, and engaging members on said bolt and retaining plate whereby the latter is moved out of locking engagement with said cylinder upon a movement of said bolt inwardly of said casing.

6. In a detachable-cylinder lock, the combination with the lock casing, of a bolt having a laterally projecting lug, a slideable cylinder-retaining plate having an opening therethrough for the key cylinder, a key cylinder formed with an annular cam shoulder and an annular locking groove in rear of said cam shoulder adapted to coöperate with an edge portion of said retaining plate around said opening for entering said cylinder through and locking the same to said retaining plate, a spring normally maintaining said retaining plate engaged with said groove, and a laterally projecting lug on said retaining plate extending across the path of movement of said bolt lug.

7. In a detachable cylinder lock, the combination of a lock casing and bolt, a detachable key cylinder, a cylinder-retainer located within said casing, and operative connections between said bolt and said retainer whereby said retainer is disengaged from the cylinder to permit removal of said cylinder upon movement of said bolt to abnormal position.

KONSTANTINE THULANDER.
